VEHICULAR SIGNAL LAMP LENS

Robert E. Dawson, Huntingdon Valley, Pa., assignor to
R. E. Dietz Company, Syracuse, N.Y.

Filed Sept. 18, 1967, Ser. No. 8,640

Term of patent 14 years

Int. Cl. D12—99

U.S. Cl. D48—32

FIG. 3

FIG. 5

FIG. 4

FIGURE 1 is a front elevational view of a vehicular signal lamp lens embodying my new design the back surface configuration of the lens being omitted for convenience of illustration, it being understood that the lens pattern is visible through the transparent face;

FIGURE 2 is a side elevational view thereof the opposite side being a mirror image of that shown, and the interior lens pattern being omitted for convenience of illustration;

FIGURE 3 is a back elevational view thereof, it being understood that the concentric ring configurations shown in the sector continue all around the back surface as indicated;

FIGURE 4 is an enlarged fragmentary view of the sector shown in FIGURE 3; and

FIGURE 5 is a sectional view on the line 5—5 of FIGURE 1.

I claim:

The ornamental design for a vehicular signal lamp lens, as shown and described.
